Gottlieb Beurer

United States Patent Office.

GOTTLIEB BEURER, OF BROOKLYN, NEW YORK, ASSIGNOR TO HIMSELF
AND F. ZIMMERMAN.

Letters Patent No. 74,193, dated February 11, 1868.

IMPROVED BEDSTEAD.

The Schedule referred to in these Letters Patent and making part of the same.

TO ALL WHOM IT MAY CONCERN:

Be it known that I, GOTTLIEB BEURER, of the city of Brooklyn, in the county of Kings, and State of New York, have made certain new and useful Improvements in the Construction of Bedsteads; and I do hereby declare that the following is a full, clear, and exact description of the construction and operation of the same, reference being had to the annexed drawings, making a part of this specification, in which—

Figure 1 represents a perspective view of my improved bedstead when set up ready for use.

Figure 2 is a top view of the same, the head-blocks being removed, and the folding grate shown in red outline.

Figure 3 is a perspective view of a side piece, combined with an end piece of the same, shown detached ready for being packed for shipping.

Figure 4 is a detached perspective view of the central piece, by means of which the side pieces are combined.

Figure 5 is a perspective view of the clamp used for securing the end pieces together on their lower part.

Figure 6 is a side view of one of the head-blocks used for securing the upper ends of the end pieces.

Similar letters of reference indicate corresponding parts in the several figures.

The nature of my invention consists in constructing bedsteads with the legs of the same forming part of the side pieces of the same, and having the side pieces as well as the end pieces made and cut vertically in halves, and provided on their joints with dove-tail projections, and having simple wood fastenings fitted to the said dove-tail projections, so that by means of the said fastenings the whole of the bedstead is readily secured together for use, or it may be easily taken apart, and may be packed in a box of the usual size and dimension used for packing the parts of mattresses, whereby the shipping of the bedstead is greatly facilitated and economized.

To enable others skilled in the art to make and use my invention, I will proceed to describe its construction and operation.

A A represent the side pieces of the bedstead, and B B are the end pieces of the same. C C C C are the bed-posts, which serve as legs to the bedstead, and they are firmly secured with the ends of the sides A A of the same, instead of usually attaching the said posts C C to the end pieces of the bedstead. Now, in order that the side pieces may be packed in like boxes, such as used commonly for shipping mattresses, which are made usually in three equal parts for each bed, I divide and form each side piece of two halves to come apart at one half of its length, and supply the same with legs D D to provide it with a resting-place; and in order to secure these halves together, I provide the same, on their opposite ends, with dowel-pins E E, to meet in the holes F F of the opposite parts, and provide the said ends with dove-tail grooves G G on their inner side, into which the ends of a central cross-bar, H, are fitted, with corresponding tongues I I, so that when these halves are brought together the dowels E E will enter into the holes F F and, by means of the placing of the cross-bar H between the sides of the bedstead and inserting their tongues I I into the notches or grooves G G, each of the sides A A is made whole, and is secured together and prevented from spreading or springing apart, whereby the sides A A may be readily detached to be packed, and, by means of being only half of the usual length, they may be packed and shipped in similar boxes as those used for the mattresses. The end pieces B B, I divide also centrally, as shown, and, in order to secure the same firmly together when used, I provide each side, on its inside, with a dove-tail shaped projecting tongue, K, of which one-half is attached to each part at the joint of the two parts, forming one end piece, B, and have a dove-tail shaped grooved block, L, fitting over the tongue K, which serves to secure the lower ends of the said halves of the end piece B. The top ends of the end pieces B, I provide with small head-blocks M M, shown in fig. 6, which serve the purpose to cover the place of the joint, and, having the dowels N N fitting in corresponding openings O O, they serve also to secure the halves the end pieces together. P P are dowels, which are made to enter corresponding holes R R in the joint of the halves of the end pieces in order to guide the same horizontally. The end pieces may be attached by hinges to the side pieces A A, where they join on one another, as shown in the drawing, so that when the bedstead is packed the same may fold, as shown in fig. 8, or they may be attached together by other fastening, to be vertically withdrawn from one another and each packed and laid in the box separately.

From the foregoing it will be clearly seen that the bedstead constructed of the parts and in the manner shown can readily be shipped with the mattresses in boxes, which are easy for transportation, in handling them, and not expensive on account of taking up room, which is so much more than actually required for its volume as a solid body.

What I claim as my invention, and desire to secure by Letters Patent, is—

Constructing the sides A A, with the posts C C C C and legs D D D D, and made in halves, as shown, and provided with the cross-bar H, combining said halves, in combination with the end pieces B B, constructed in the manner substantially as herein shown, and for the purpose described.

GOTTLIEB BETTER.
